UNITED STATES PATENT OFFICE.

HARRY FORDE, OF TORONTO, ONTARIO, CANADA.

PASTEURIZER-COIL BRUSH.

1,270,137.

Specification of Letters Patent. Patented June 18, 1918.

Application filed October 4, 1917. Serial No. 194,752.

To all whom it may concern:

Be it known that I, HARRY FORDE, a subject of the King of Great Britain, residing at Toronto, in the Province of Ontario and 5 Dominion of Canada, have invented certain new and useful Improvements in Pasteurizer-Coil Brushes, of which the following is a specification.

This invention has relation to brushing 10 and cleaning devices, and has for an object to provide a device particularly adapted and intended to clean the exterior surface of the revoluble coil of a milk or cream pasteurizing machine.

15 Another object of the invention is to provide a device for the purpose above described which embodies a pair of semicircular brushing elements mounted for movement toward and away from each other and defining, when the brushes are in proper relation 20 a circular brushing element designed to encircle the pipe forming the coil of a milk or cream pasteurizing machine whereby the exterior surface of the entire coil may be 25 cleaned in one operation.

Another object of the invention is to provide a brushing device having the above named characteristics and including the 30 semi-circular brushing elements, and a new 30 and novel means whereby the brushing elements may be moved toward or away from each other to permit the same to be encircled about the pipe forming the coil of a milk or cream pasteurizing machine.

35 In addition to the foregoing my invention comprehends improvements in the details of construction and arrangement of the parts to be hereinafter more fully described and particularly set forth in the appended 40 claims.

In the accompanying drawings in which similar and corresponding parts are designated by the same characters of reference throughout the several views in which they 45 appear:

Figure 1, is a view in plan of a brushing and cleaning device constructed in accordance with my invention.

Fig. 2, is a view of the device in side elevation, and

Fig. 3, is a detail section taken on the line 3—3 of Fig. 1.

With reference to the drawings, 10 indicates a handle having a hand grip 11 on one 5 end, and a pair of oppositely extending ears 12 at its opposite end, said ears being aper-

tured. A pair of semi-circular brush elements 13 are provided, each brushing element having one end bifurcated as at 14 to receive therebetween the ears 12 of the handle, whereby a pin 15 inserted through the bifurcated end of the brushing element and through the apertured ear 12 may serve to connect the brushing elements to the handle for movement. The brushing elements 13 as stated above are semicircular and are arranged so as to define a complete circle when the free ends of the elements are brought into proximity as shown in Fig. 1. The inner surface of each curved element 13 is provided with bristles 15', the bristles on the free ends of the elements being longer than the remaining bristles as indicated at 16 and directed toward each other so as to form a complete circle of bristles when the elements 13 are in arrangement to define a circle. The end of the handle 10 to which the brushing elements are connected is also provided with a set of bristles 17, forming with the bristles of the curved elements a 80 complete circular arrangement. A pair of springs 18 are provided one for each pin 15 which they encircle, one end of each spring being secured to the handle while the other bears against the outer surface of an adjacent brushing element 13 whereby to urge said elements toward each other.

To separate one of the elements 13 from the other, I provide an arrangement on the handle which comprises a pair of laterally 90 extending ears 19 and 20, a member 21 being secured to the standard 19 to form a guide, said member 21 being apertured to receive a rod 22 to guide the same. One end of the rod is connected to one of the members 13 while the other end is connected to a substantially bell crank shaped member 23 having one end extended to form a finger grip 24, the bell crank being pivotally mounted upon the ear 20.

A certain type of milk and cream pasteurizing machines includes a coil of pipe having its convolutions spaced and mounted for rotation around the longitudinal axis of the coil. It is this coil that my device is 105 intended to clean and when in use the hand grip 11 is grasped and the finger grip 24 pressed so as to move the associated brushing element 13 away from its mating element to permit the brushing element to encircle one of the convolutions of the coil at 110 one end. The semi-circular brushing ele-

ment is then permitted to return to its former position so as to define a circle and permit the bristles to engage around the pipe. The provision of the bristles 16 and 17 permit each portion of the circumference of the pipe to be engaged whereby when the coil is rotated and the device held stationary, the pipe forming the coil will be cleaned throughout its length, the brushing device being moved along the coil in a longitudinal direction as the coil rotates. The cream, butter fat and substances which cake on the convolutions of the coil, are thus removed in one operation and in a cleanly manner.

Having thus described my invention what I claim as new and desire to secure by Letters Patent is:—

1. A brushing device including a handle, 20 a pair of semi-circular brushing elements mounted thereon to define when the brushing elements are brought together a complete circle, resilient means urging the brushing elements toward each other, and 25 means mounted on the handle engaging one of the elements to move the same away from the other.

2. A brushing device including a handle, 30 a pair of semicircular brushing elements pivotally mounted thereon, defining when brought together, a complete circle, resilient elements urging the brushing elements toward each other, a bell crank mounted on

the handle, and means operable by movement of the bell crank to move one of the 35 brushing elements away from the other.

3. A brushing device including a handle, a pair of semicircular brushing elements mounted thereon to define when brought together, a complete circle, resilient means for 40 urging the brushing elements toward each other, a pair of laterally extending ears on the handle, one ear forming a guide, a bell crank mounted on the other ear, and a rod connecting said bell crank to one of the 45 brushing elements whereby to move the same away from each other.

4. A brushing device including a handle, two pairs of apertured ears on one end of the handle, and at opposite sides of the 50 handle, a pair of semi-circular brushing elements, each being pivotally connected at one end thereof between a pair of ears, studs penetrating said ears and brushing elements and extending therebeyond and a coil spring 55 surrounding each stud, each spring having one end connected to one of the associated brushing elements, and its other end connected to the handle to urge said brushing elements toward each other. 60

In testimony whereof I affix my signature in presence of two witnesses.

HARRY FORDE.
